CATHARINE A. GRISWOLD, OF NEW YORK, N. Y.

DESIGN FOR THE ORNAMENTATION OF CORSETS.

SPECIFICATION forming part of Design No. 17,080, dated February 1, 1887.

Application filed December 1, 1886. Serial No. 220,418. Term of patent 14 years.

To all whom it may concern:

Be it known that I, CATHARINE A. GRISWOLD, of the city of New York, county and State of New York, and a citizen of the United States, have invented and produced a new and original Design for the Ornamentation of Corsets, of which the following is a full, clear, and exact description, reference being had to the accompanying drawing, forming part of this specification.

The single figure in the drawing represents in side elevation a corset embodying my new design.

The leading features of my design are ornamental bands or stripes on the outward face of the corset, extending, each having a curve, upwardly from the bottom edge on the front of the corset, one over the hip portion of each of the sides or halves of the corset, and returning to said bottom edge on the rear of the corset, and a series of ornamental bands or stripes extending at intervals from the top edge of the corset downwardly, each having a curve toward the waist-line and returning upwardly to said top edge.

A is the corset, which may have the usual and ordinary general form.

B represents an ornamental band or stripe, which extends on the outward face of the corset upwardly in a curve from the bottom edge on the front over the hip portion, and returns downwardly to said bottom edge on the rear of the corset. It is intended that one of these bands B shall extend, as described, over the hip portion of each side or half of the corset.

At C C' C² are represented ornamental bands or stripes, which extend in a series at intervals, each having a curve downwardly from the top edge of the corset toward the waist-line, and returning to said top edge again. In the drawing one of these bands, C, is shown encircling a breast-swell, D, from the top edge of the corset downwardly, and the series of said bands is completed by one under the arm and another on the rear of the corset.

What I claim is—

The design for the ornamentation of a corset herein shown and described, which consists of a corset, A, having on its outward face ornamental bands B, extending from the bottom front edge upwardly in a curve, one over the hip portion of each side or half of the corset, and returning to said bottom edge on the rear, and a series of ornamental bands, C C' C², extending from the top edge of the corset downwardly, each having a curve toward the waist-line, and returning to said top edge, as set forth.
